[57] CLAIM

The ornamental design for a buckle, as shown and described.

DESCRIPTION

FIG. 1 is a side view of the buckle incorporating my new design.

FIG. 2 is a front or end view of the buckle of FIG. 1.
FIG. 3 is a side view of the buckle of FIG. 2 opposite the side shown in FIG. 1.

FIG. 4 is a view of the buckle end opposite the end shown in FIG. 2.

FIG. 5 is a top view of the buckle of FIG. 2.

FIG. 6 is a bottom view of the buckle of FIG. 2.

FIG. 7 is a cross-sectional view taken along the line 7—7 of FIG. 5 and viewed in the direction of the arrows.
